SWITCH AND RHEOSTAT

John H. Little, Royal Oak, Mich., and Arnold A. Bluemle and William Earl Brown, Anderson, Ind., assignors to General Motors Corporation, Detroit, Mich., a corporation of Delaware

Application July 16, 1940, Serial No. 345,798

7 Claims. (Cl. 201—48)

This invention relates to electrical control apparatus and more particularly to a combined electric switch and rheostat.

An object of the present invention is to provide a single operating member which can be reciprocated and rotated to control a plurality of switch mechanisms wherein longitudinal movement of the operating member actuates one switch to control a plurality of circuits and rotary movement controls a rheostat connected in one of the circuits.

Another object of the present invention is the provision of novel structures for interconnecting a single control rod with the movable parts of a rotatable switch unit and of a reciprocable switch after both switches have been installed in a predetermined position to a fixed support.

Another object of the invention resides in the specific structures of the movable units of a plurality of switches and their connections with a single actuator.

Another object of the present invention is to provide a novel arrangement whereby two switches may be mounted on a single bracket and actuated by the same rod and each switch is operated in a desired manner in response to certain movements of the rod and whereby one switch may be actuated by the rod without effecting the position of the other switch.

Further objects and advantages of the present invention will be apparent from the following description, reference being had to the accompanying drawings wherein a preferred embodiment of the present invention is clearly shown.

In the drawings:

Fig. 1 is a front view of the combined switch and rheostat.

Fig. 2 is a sectional view taken on the line 2—2 of Fig. 1.

Fig. 3 is a rear view of the combined switch and rheostat.

Fig. 4 is a sectional view taken on the line 4—4 of Fig. 2.

Fig. 5 is a sectional view taken on the line 5—5 of Fig. 1.

Fig. 6 is an end view of the switch looking in the direction of arrow 6 in Fig. 1.

Fig. 7 is a detail plan view of the block for receiving a rheostat.

Fig. 8 is a plan view of the block and rheostat assembly.

Fig. 9 is a sectional view taken on the line 9—9 of Fig. 8.

Fig. 10 is a sectional view taken on the line 10—10 of Fig. 2.

Fig. 11 is a front sectional view showing parts of the switch actuator and rod shown in Fig. 2 in assembled relation.

Fig. 12 is a wiring diagram of the lighting circuit controls by the combined switch and rheostat shown in Figs. 1 to 11 inclusive.

Fig. 13 is a front plan view of a modified form 10 of a combined switch and rheostat.

Fig. 14 is an end view of the combined switch and rheostat shown in Fig. 13.

Fig. 15 is a sectional view taken on line 15—15 of Fig. 13.

Fig. 16 is an end view of the switch looking in the direction of arrow 16 in Fig. 15.

Fig. 17 is a sectional view taken on line 17—17 of Fig. 15.

Fig. 18 is a sectional view taken on line 18—18 of Fig. 15.

Fig. 19 is a sectional view taken on line 19—19 of Fig. 15.

Fig. 20 is a wiring diagram of the lighting circuits controlled by the combined switch and 25 rheostat shown in Figs. 13 to 19 inclusive.

Referring to the drawings 20 designates a bracket of L-shaped formation comprising arms 21 and 22. The bracket is adapted to be supported from a panel 23. The panel 23 and the 30 arm 22 of the bracket 20 are provided with aligned openings. In the present instance the opening in the arm 22 is formed by forcing a portion of the arm 22 out of its normal plane into a tubular portion 25 which is internally 35 threaded to receive the threaded shank of a flanged bushing 26. The outer face of the flange of the bushing 26 is provided with suitable notches or about the bore of the bushing to receive a key whereby the bushing may be 40 threaded into tubular portion 25 to clamp the arm 22 of L-shaped bracket firmly against the rear face of the panel 23.

The arm 21 of the bracket is provided with a bearing opening 30 and an elongated slot 31, the 45 marginal walls of the slot 31 are deformed out of the plane of the arm 21 to provide a channel shaped recess 33. A switch casing 34 of cupped formation is attached to the arm 22 in any suitable manner, such as spot welding. The casing 34 is closed by dielectric terminal head or closure 35 carrying stationary terminals 36, 37, 38, 39, 40 and 41. The bottom wall 42 of the casing 34 is provided with a bearing aperture 43 and an elongated slot 44. When the casing is 50 secured to the arm 22, the opening 44 and the slot 55

43 will be in alignment with the opening 30 and slot 31 respectively. The channel shaped recesses 33 and bottom wall of the casing 34 form channels 45 between the casing and the bracket.

Before the casing 42 is attached to the arm 22 an actuator unit 50 is assembled with the elements. The actuator unit 50 comprises a U-shaped member having arms 51 and 52 connected by a yoke 53. Each arm of the U-shaped member is provided with an aperture, the arm 51 has a bearing aperture 54 while the arm 52 is provided with an enlarged aperture 55 through which a shaft 60 may loosely pass. The yoke 53 carries a pin or post 61 having a collar portion 62 and a shank portion 62a. The collar 62 projects into the channels 45 formed by the arm and housing, said collar having a sliding fit within the channels and assists in guiding the actuator longitudinally in the slots. The collar also prevents the actuator unit 50 from being disassembled from the arm 22. A flat spring of L-shaped formation has one of its arms 64 thereof attached to the yoke 53. This is accomplished in the present instance by riveting over one end of the pin 61 against the upper face of the spring. The other arm 65 of the spring is biased upwardly as viewed in Fig. 2. The arm 65 is provided with an opening 66 through which the rod 60 may loosely pass. The lower end of the opening 66 is reduced as at 66a, see Fig. 11. A portion of the arm 64 of the spring is struck out to form a lug 67. This lug 67 extends into a slot 63 in the arm 52 of the U-shaped member to prevent the spring from rotating relative to the arm. The yoke 53 is also struck out to provide an extension 68 which projects into the elongated slot of arm 21 to prevent the actuator from turning relative to the arm 21.

The shank portion 62a of the post 61 projects through the elongated slots 31 and 44 of the arm and bracket respectively and extends into a radial slot 71 provided on one side of a dielectric rotor 72. The radial slot 71 is adjacent the inside surface of the bottom wall 42 of the casing. The other side of the rotor is provided with a recess to receive a compression spring 73 which urges a movable contact 74 drivingly supported on the rotor 72 against the stationary terminals carried by the closure 35. The spring 73 also operates to maintain a boss 75 carried by rotor within the bearing openings 30 and 43 provided in the arm 21 and the bottom wall of the casing and also to maintain the shank portion 62a in the radial slot 71.

The arm 22 supports a U-bracket 80 having arms 81 and 82 provided with aligned apertures through which the shaft 60 may loosely pass. The arm 82 carries an insulating block 83 having a counterbored opening 83a in alignment with the opening in the arm 82. Within the counterbored opening is housed a coil spring 84 and an insulating washer 85, the spring 84 having one end resting on a shoulder formed in the opening 83a and the other end engaging the washer 85 to urge the washer 85 against the end of a tubular portion 86 formed on a disc portion 87 provided at one end of a conducting strip 88. The conducting strip 88 is attached to the insulating block 83 by a tubular rivet 89 see Fig. 8.

The block 83 is provided with an arcuate recess 90 about the opening 83a. A resistance element 91 is supported within the recess 90. The resistance element comprises a helically wound wire and has one end bearing against a shoulder 90a and the other end of the wire unit extends

through an opening 93 in the block which is electrically connected to a tubular rivet 94. The rivet 94 also secures a conducting strip 95 to the block 83. The conducting strips 88 and 95 are spaced from each other by a projection 96 provided on the front face of the block.

An insulating bushing 100 having a flange 101 and a shank 102 is disposed between the arm 81 of the U-bracket 80 and the insulating washer 85. The shank 102, see Fig. 10, is provided with flat sides on its exterior surface and the interior of the shank is non-circular. A movable contact 103 is supported on the shank. This contact comprises a disc portion 104 having an opening 105 forming in outline to the exterior surface of the shank so as to be driven thereby. The contact 103 is provided with two arms 105 and 105a. Each arm is provided with a boss. The boss of arm 105 is urged into frictional contact with the resistance unit 91 while the boss of arm 105a is urged into electrical engagement with the flat surface of the disc portion 87 of the strip 88 by a spring 106 about the shank 107. The spring is disposed between the flange 101 of the bushing 90 and the disc portion 104 of the movable contact. The other end of the strip 88 is electrically connected to the terminal 40 carried by the closure 35.

The contour of the rod 60 conforms with the non-rounded interior of the bushing 100 so as to drive same. The inner end of the shaft 60 is provided with a conical or cam surface 108 and a shaft portion 109 with the shaft portion supported in the bearing opening 54 in the arm 52. The outer end of the rod carries a knob 110. The bushing 26 forms the other bearing for the rod. The rod 60 is provided with an annular groove 111 intermediate its ends and said groove is so positioned on the rod 60 that when the rod is in its assembled relation the groove 111 will be just inside the arm 51 of the bracket 50.

When the rod is assembled with its associated elements, the rod is first passed through the bearing bushing 26 and then the rod is rotated until the non-rounded contour of the shaft registers with the inside bore of the bushing 100. When that registration occurs further inward movement of the rod will cause the shaft portion 108 of the rod to pass through the openings in the arms 51 and the arm 63 of the spring member. At this point the enlarged portion of the opening is somewhat out of alignment with the opening in the arm 51. Therefore the cam surface 108 of the rod comes in contact with the reduced portion 66a of the opening 66, consequently when the rod is moved further the arm 63 will be moved against the bias of the spring so that the rod can pass through the opening 66 until the shaft portion 109 engages the bearing in the arm 51. When the shaft portion 109 fits into the bearing opening 54 the spring will snap, due to its own resiliency, into the annular groove 111. When this occurs the rod 60 will be interlocked with the spring 63 and maintain the shaft in assembled relation with the actuator 52, but permits the rod 60 to rotate in its bearings.

The limits of longitudinal movements of the actuator 50 and the rotative movement of the movable switch mechanism are defined by the ends 70 of marginal walls of the slots formed in the bottom wall and the arm 22. In order to operate the switching mechanism within the casing the rod 60 is reciprocated to move the actuator 50. When this happens the end of the post 61 which projects into the radial slot 71 of the rotor

12 will cause the rotor to rotate in the bearing openings 30 and 43 in the arm 21 and the bottom 42 respectively. It is to be stated here that so long as the rod 60 is not rotated the movable contact 103 will remain stationary. When the knob 107 is rotated, the rod 60 will drive the insulating bushing 100 which in turn will drive the movable contact 103 causing the arms 105 and 105a to slide frictionally over the resistance coil 91 and disc 87, respectively.

Referring to Figs. 13 to 20, inclusive, a modified form of the present invention is shown. In the modified form of the invention the L-shaped bracket 120 has arms 121 and 122. The arm 121 is provided with an opening formed by forcing a portion of the arm 121 inwardly to provide a tubular portion 124 which is internally threaded, to receive a flanged bushing 125. The flanged bushing in this instance forms a bearing for an actuating rod 126.

The arm 122 of the bracket is provided with an elongated guide slot 127 intermediate its length and supports a switch 128. The switch comprises a rectangular casing 129 provided with marginal tongues 130 on its side walls which are bent over against a closure 131 of insulating material to complete the switch assembly. The closure 131 carries a plurality of stationary terminals the arrangement of which will be set out later. The stationary terminals have their inner ends thereof flush with the inner face of the closure 131.

The movable contact mechanism for the switch comprises a metal plate or slide 132 fitted for reciprocation within the switch casing 129. This slide comprises a metal plate having a rectangular head portion 133 with the side edges thereof adjacent the side walls so as to be guided by the side walls of the casing 129 and a long arm 134 which extends through an opening 135 in an end wall 136 of the casing 129. The free end of the arm is bent downwardly and is provided with a reduced portion projecting into and having a sliding fit with the slot 127 to assist in guiding the plate in its longitudinal movements.

The central section of the head portion 133 of the plate 132 is apertured to receive a reduced portion of a counterbored sleeve 136. The sleeve is attached to the head portion 133 by spinning over the sleeve against the bottom face of the slide. The smaller bore dimension of the sleeve houses a ball 137 which normally rests in one or the other of depressions 138 formed in the bottom wall of the casing. The corners of the head portion 133 of the plate 132 are partially severed therefrom and the severed portions are bent upwardly to provide four prongs 139. These prongs are adapted to guide a block 140 of insulating material which has notched corners to receive the prongs 139. The lower side of the block has a recess 141 the bottom of which forms a seat for one end of a spring 142. The other end of the spring 142 rests on a shoulder provided by the counterbore in the sleeve 136. The spring 142 operates in one direction to urge a contact plate 143 carried on the upper surface of the block into contact engagement with the inner surface of the closure 131 and in the other direction to urge the plate 132 against the bottom wall of the switch casing. A small compression spring 144 is confined within the spring 141. The spring 144 has one end seated against the bottom of the recess 141 and the other end engaging the ball 137 to urge the ball against the bottom wall of the casing. Three depressions

138 are formed in the bottom wall of the switch casing 129 in straight alignment and are in the longitudinal path of the ball 137 which moves with the slide 132. The depressions indicate the various positions of the slide.

A flat spring 150 is attached to the plate 132 by the sleeve 136. This is accomplished by having the reduced portion of the sleeve passing through a suitable opening in the spring and spun over the lower face of the plate 132. The spring 150 is so formed and arranged with respect to the plate 132 that the free end of the spring is biased upwardly. The free end of the spring 150 carries an L-shaped bracket which has one arm 151 attached to the spring by rivets. The other arm 152 of the bracket extends beyond the free end of the spring and projects downwardly. The arm 152 is provided with a slot having a portion larger than the diameter of a rod 126 and having a narrow portion equal to the diameter of reduced portion of the rod which is formed by cutting an annular groove 154 at the inner end of the rod.

A resistance unit 160 is supported on the arm 122. This unit comprises a U-shaped bracket 161 having arms 162 and 163. Each arm is provided with an aperture through which the rod 126 may loosely pass. The arm 162 carries an insulating block 164 having a counterbored opening 165 in alignment with the openings of the arms 162 and 163. Within the counterbored opening of the block 164 is housed a coil spring 166 and an insulating washer 167, the spring has one end engaging a shoulder provided by the counterbored opening and the other end engaging the washer 167 to urge same against the end of a tubular portion 168 formed in a metallic disc 169.

The inner face of the block 164 is provided with a pair of segmental grooves 171 and 172 arranged concentrically with respect to the counterbore 165. A pair of resistance elements 173 and 174 comprising helically wound wire is formed to lie in the bottom surface of the grooves 171 and 172 respectively and are adapted to be retained in the grooves by one end of conducting members 175 and 176 which are electrically connected to one end of the coils 173 and 174, respectively, by tubular rivets 177 and 178 respectively. The other end of the conducting members 175 and 176, respectively are connected to suitable lead wires to lamp or other consuming devices. It will be noted that the grooves partially overlie the coils, see Fig. 19, thereby ensuring against upward movement of the coils out of the grooves. By this arrangement the free ends of the coils need not be fixed to the block.

A bridging contact 180 punched and stamped from sheet metal is provided with a non-circular opening 181 formed in a central portion 182. The bridging contact has two diametrically opposed arms 185 and 186. The bridging contact 180 is drivingly supported upon an insulating bushing 187 having a flange 188 and a shank 189. The bushing is disposed between the arm 163 of the U-bracket 161 and the insulating washer 167. The contact arms 185 and 186 are urged into frictional contact against the inner face of the block 164 by a coiled spring 190 about the shank 189 and having one end bearing against the flange 188 and the other end against the central portion 182 of the contact 180.

The slide is actuated by the control rod 126 having a flat side 192 and having a conical

portion 193 at its inner end. The outer end of the rod 126 supports an insulating knob 193. Adjacent the conical end 193 of the rod there is provided an annular groove 194. To assemble the rod 126 with the plate 132 the conical end 193 of the rod is first passed through a bushing 26 and then through the aligned openings provided by the resistance unit. It is to be understood that the flat side of the rod registers with the interior contour of the bushing 187. In case the contours of the bushing 187 and the rod 126 do not register the rod is rotated until the registration occurs. The rod then is pushed inwardly until the conical end 193 projects through the opening of the bracket. As soon as the annular groove 194 is in the same vertical plane of the arm, the spring 150 will snap the bracket upwardly into the groove which interlocks the operating rod 126 with the spring 150. Longitudinal movement of the rod 126 on the front side of the panel 23 then serves to shift the plate from one position to another, the plate being held in its selected position by the action of the spring 144 forcing the ball 137 downwardly to seat in one of the depressions.

If it is desired to rotate the contact 180 so that the arms 185 and 186 will engage the coils 173 and 174 the knob is rotated. The contacts are adapted to rotate 180°. A stop 200 formed integral with the block controls the limit of rotary movement of the contact arms.

The stationary terminals carried by the closure 131 and which have been referred to as having their inner ends flush with the inner face of the closure will now be described. The closure 131 supports a conducting bracket 224 outside the closure. The bracket which supports at one end thereof a plurality of terminal screws 226. The bracket is attached to the closure 131 by rivets 227. The other end of the bracket 225 supports an adjustable contact 228 normally engaged by a movable contact 229 carried on the free end of a thermostatic strip 230. The other end of the thermostatic strip 230 is electrically connected to an elongated conducting plate 231, shown diagrammatically in Fig. 20. Paralleling the conducting plate 231 are three stationary terminals, a "dimmer" switch terminal 232, a "tail" lamp terminal 233, and a "park" light terminal 234. The terminal 232 is electrically connected by a lead 235 to the common terminal of a dimmer switch, 236. The terminal 233 is connected by a lead 237 to the conducting member 175. The terminal 234 is connected by a lead 238 to the "park" lamps 240. The conducting strip 231 is connected to a terminal 241 supported on the block 164. The "tail" lamp 242 is connected to the conducting member 175 by a lead 243. It is to be understood that the tail lamp could be connected to the lead 243 to the terminal 233.

The switch structure shown in detail in Figs. 1 to 12, inclusive, is useful in controlling the various lighting circuits of an automotive vehicle. The circuits adapted to be controlled in this instance is shown diagrammatically in Fig. 13. It is to be stated here that the stationary contact terminals 36, 37, 38, 39, 40 and 41 are supported on the closure 135 are arranged in a circular row and that the terminal 36, 37 and 40 and 41 are connected together by conducting plates 201 and 202, respectively, and that the plates 201 and 202 are only shown in the diagram. In the diagram 203 designates a storage battery having one terminal grounded at 204. The other terminal of the battery is connected

to the plate 201 by a lead 205 through a fuse 206. The head lamps 207 having "dim" filaments 208 and "bright" filaments 209 are adapted to be alternately connected in a circuit by a dimmer switch 210 having a live terminal 211 connected by a lead 212 to terminal 38. The terminal 39 is connected to the "parking" lamps 213 by a lead 214. The plate 202 is connected to the contact by the strap 88. The resistance coil is connected to the conducting plate 95 which is in turn connected by a lead 215 to the various instrument board lamps 216. All of the lamps are grounded by the usual ground connections.

Referring to the wiring diagram the movable contact 217 is shown in dotted lines in the "off" position of the lighting switch. When the control knob is moved away from the panel the movable contact 217 will be moved in the direction of the arrow 218. In the first "on" position of the switch the movable contact will bridge plate 201, terminal 39 and plate 202 causing current from the battery 203, lead 205, fuse 206, plate 201, movable contact 217 from whence it is divided; a portion of the current will flow from contact 217, through terminal 39, lead 214, parking lamp 213 and back to battery through the ground connections. Another portion of the current will flow from the movable contact 217, terminal plate 202, lead 219, "tail" lamp 220 and back to battery through the ground connection.

Should the operator turn the rod a certain angular distance the contact arm 105 of contact 103 will engage the resistance coil 91 causing current to also flow from the plate 202 through plate 88, movable contact 103, resistance coil 91, plate 95, lead 215, through the instrument lights 221 and back to battery through ground connections. The instrument lights in this instance will burn dimly when the movable contact arm 105 is rotated to engage the conducting strip 95 the instrument light will burn brightly.

When the rod is pulled out further from the panel the movable contact will be moved to the second "on" position of the switch causing the movable contact to bridge terminals 201, 38 and 202 causing current to flow from the battery 203, lead 205, fuse 206 contact 201 and movable contact 217 from whence it will be divided; a portion of the current will flow from the movable contact 217 to the head lamps 209 through lead 212 to the live terminal 211 of dimmer switch 210. The dimmer switch is manually operated and is adapted to connect alternately the "dim" and "bright" filaments of the head lamps in a circuit. Since one or the other of the "dim" or "bright" lamps are connected in the circuit, the return flow of the current to the battery is through the ground connections. The other portion of the current will flow from the movable contact 217 through terminal 202, lead 219 tail lamp 220 and back to battery through the ground connection.

The switch structure shown in detail in Figs. 13 to 19 inclusive is useful in controlling the various lighting circuits shown diagrammatically in Fig. 20. Referring to the diagram the storage battery 203 has one terminal grounded at 204 and having the other terminal electrically connected to the conducting member 226. Both switches 128 are shown in the "off" position. When the switch 128 is actuated by the rod 126 to the left as viewed in Figs. 1, 2 and 3 to the first "on" position the triangular shaped contact 143 will bridge stationary contacts 234, 233 and 231, caus-

ing current to flow from the battery 203, lead 226a, conducting member 226, adjustable contact 228, movable contact 229 conducting plate 231, bridging contacts 143, from whence it is divided; a portion of the current will flow from the movable contact through stationary terminal 234, lead 238 through stationary terminal 234, lead 238 through parking lamps 249 and back to battery through the ground connections. Another portion of the current will flow from the movable contact 243, terminal 233, lead 237 tail light 242 and back to battery through ground connections.

In the second "on" position of the switch 128 the movable contact 243 will bridge terminals 231, 233 and 232, and disconnect the terminal 234 from the circuit. In this position the current will flow from the battery 203 in the same manner as in the first "on" position with this exception that a portion of the current will flow from the movable contact 243 to the terminal 232 and thence through the lead 235 to the common terminal 236 of the dimmer switch. The dimmer switch is adapted to connect alternately the "bright" filament 245 and the "dim" filament 246 of the head lamp 247 in the circuit only when the switch 128 is in the second "on" position.

When the operator desires to have the instrument lamp mounted on the dash board burning the knob 193 is rotated a certain angular distance in the direction of the arrow 250 see Fig. 20, to drive the movable contact 180, when the movable contact 180 is rotated until the arms 186 and 185 bridge stationary contacts 250 and 251 supported on the block 164. The contact 250 is electrically connected to a plate 252 while contact 251 is electrically connected to plate 253. The plate 252 is connected to the contact 231 of switch 128 by a lead 254 while the plate 253 is connected by a lead 255 to a lamp 256.

An instrument lamp 260 is connected to the plate 176 by a lead 257. It is to be understood that more than one lamp may be connected in parallel or series to the terminal plate 176. When the operator turns the knob 193 until the arms 185 and 186 of contact 180 engage the resistance coils 173 and 174, the instrument lamp 258 will burn dimly. When the arms engage the rivets or contacts 177 and 178 the resistance coils 173 and 174 will be short circuited and the lamp 258 will burn brightly. It will be observed that the instrument lamp 258 can be connected in a circuit only when the switch 128 is moved to one of its "on" positions while the lamp 256, suitable for reading road maps, can be connected in a circuit in any position of the switch 128.

While the embodiment of the present invention as herein disclosed, constitutes a preferred form, it is to be understood that other forms might be adopted, all coming within the scope of the claims which follow.

What is claimed is as follows:

1. A combined variable resistance and switch unit comprising a panel having an opening; a frame member attached to the panel; a resistance unit of substantially arcuate shape; a support for the resistance unit carried by the frame; a switch carried by the frame; a member slidably supported on the frame including means for actuating a movable part of the switch upon sliding movements of the member; a common removable shaft adapted for rotary and longitudinal movements adapted to be inserted through the opening from the front of the panel said shaft being provided with an annular groove; means provided by the slidable member and the frame

for supporting the shaft centrally of the resistance elements; a contact arm slidably engaging the resistance unit and rotatable with the shaft; and resilient means fixed at one end to the slid-
5 able member and having its free end biased toward the shaft, said free end being provided with opening through which the shaft passes, said opening in the resilient means being reduced to fit snugly in the groove of the shaft for interlocking the resilient means with the shaft where-
10 by said shaft is capable of imparting longitudinal movements to the member in the assembled relation of the parts.

2. A mounting comprising; an L-shaped bracket of which the one arm is provided with an aperture to provide a bearing for a shaft while the other arm is provided with an elongated slot; a cup-shaped housing having its bottom wall fixed to the second mentioned arm and having an elongated slot in alignment with the slot in said arm; a U-shaped member having each arm provided with apertures with one aperture being larger than the other the larger opening permitting a shaft to pass loosely therethrough while the other opening provides a bearing for a shaft; means carried by the U-shaped members extending through the elongated slots of the housing and the bracket and adapted to actuate movable means within the housing; a removable shaft adapted for longitudinal movements, and supported in the bearing apertures, said shaft having an annular groove; a spring member fixed at one end to the U-member and having its free end biased upwardly, a portion of the free end being cut out to form a slot of a size to allow the shaft to pass therethrough, said slot having a narrow portion to fit into the groove of the shaft where-
20 by said shaft is adapted to impart longitudinal movements to the U-member in the assembled relation of the elements.

3. A combined variable resistance and switch unit comprising; a frame; a resistance unit of substantial arcuate shape; a support for the resistance unit carried by the frame; a switch carried by the frame; a bracket slidably supported upon the frame including means for actuating the switch upon sliding movements of the bracket; a removable shaft adapted for rotary and longitudinal movements, said shaft being provided with an annular groove; spaced apertured arms provided by the frame and bracket to provide bearings for the shaft and to support the shaft centrally of the resistance unit; a contact arm slidably engag-
40 ing the resistance unit and rotatable with the shaft; and a resilient member fixed at one end to the bracket and provided with an opening at its free end through which the shaft passes, said opening being reduced to fit snugly between shoulders formed by the groove, said resilient member being sufficiently strong to maintain the reduced portion between the shoulders of the groove whereby said shaft is adapted to impart movements to the bracket when the shaft is moved longitudinally in the assembled relation of the parts.

4. A combined variable resistance and switch unit comprising; a frame; a resistance unit sub-
70 stantially arcuate in shape; a support for the resistance unit carried by the frame; a switch carried by the frame; a bracket slidably supported upon the frame including means for actuating the switch upon sliding movements of the bracket; a removable shaft adapted for ro-

tary and longitudinal movements, said shaft being provided with an annular groove; spaced apertured arms provided by the frame and bracket to provide bearings for the shaft and to support the shaft centrally of the resistance unit; an insulating bushing supported relative to the resistance unit through which the shaft extends; a contact arm supported on the bushing whereby upon rotation of the shaft said bushing and contact will be rotated therewith, said arm being in frictional contact with the resistance unit; and a resilient member secured at one end to the bracket with the free end inclined upwardly with a portion of the free end being cut out to form a slot of a size to allow the shaft to pass through, said slot having a narrow portion to register with the groove whereby said shaft is capable of imparting sliding movements to the bracket in the assembled relation of the parts.

5. A switching mechanism comprising a plurality of circuit controllers adapted to be mounted on the one side of a support and including a plurality of movable elements and a frame adapted to be mounted over a bearing aperture in the support; a non-rounded rod adapted to be inserted through the bearing aperture in the support and through a non-rounded aperture in a part of one of the movable elements, the inner end of the rod having a reduced portion adapted to extend into a bearing aperture in another movable element and having a perimetrical groove; and a yieldable member carried by the second mentioned movable element, said yieldable element having an opening through which the rod passes, the opening being reduced at one side to fit into the perimetrical groove of the rod so as to interlock the yieldable element with the rod whereby the rod is capable of imparting longitudinal movements to the second mentioned movable element and rotary movements to the first mentioned movable element in the assembled relation of the parts.

6. A switching mechanism comprising a combined switch unit and a resistance unit; a longitudinally movable member for actuating a contact carrier of the switch unit; a rotatable contact carrier for the resistance unit; a non-

rounded rod adapted to pass through a non-rounded opening provided by the rotatable carrier, said rod being provided with an annular groove intermediate its end; and a resilient member fixed at one end to the longitudinal movable member and having its free end biased toward the axis of the non-round opening of the contact carrier, said free end having an opening of such size to permit the inner end of the rod to pass therethrough, said opening also having a narrow portion adapted to fit into the annular groove to interlock yieldingly the longitudinal movable member with the rod and to permit rotation of the rod in the assembled relation to drive the rotatable carrier.

7. An electrical control device including a plurality of circuit controllers adapted to be mounted on one side of a panel, comprising a bracket having an arm provided with an opening adapted to be supported in axial alignment with an opening in the panel; a variable resistance and a switch mounted on another arm of the bracket and in spaced relation; actuating means for a movable part of the switch and of the variable resistance; a common removable operating shaft for operating the actuating means, said shaft adapted to be inserted from the other side of the panel through the openings of the panel and bracket arm and having a rotatable driving association with the actuating means for the resistance, the inner end of the shaft being rotatably supported on the actuating means for the switch; a yieldable element fixed to the actuating means for the switch; and cooperating provisions provided by the shaft and the yieldable element for interlocking the element with the shaft whereby the shaft is capable of longitudinal movement to operate the switch actuating means without effecting the position of the resistance actuating means, said cooperating means also permitting rotational movements for the shaft so as to drive the actuating means for the resistance without changing the position of the switch actuating means in the assembled relation of the parts.
